UNITED STATES PATENT OFFICE.

WILLIAM J. TAYLOR, OF CHESTER, ASSIGNOR TO THE TAYLOR GAS PRODUCER COMPANY, OF CAMDEN, NEW JERSEY.

GAS-PRODUCER.

SPECIFICATION forming part of Letters Patent No. 399,793, dated March 19, 1889.

Application filed December 31, 1886. Serial No. 228,112. (No model.)

To all whom it may concern:

Be it known that I, WILLIAM J. TAYLOR, of Chester, in the county of Morris and State of New Jersey, have invented certain new and useful Improvements in Gas-Producers, of which the following is a specification.

My invention relates to a furnace or plant for gasifying fuel for making heating-gas or converting solid fuel into gaseous fuel, and such as is generally designated in iron metallurgy as a "gas-producer," yet differing from the producer in common use, inasmuch that brick linings are entirely dispensed with, and which apparatus, constructed of metal and water-cooled, as hereinafter described, I have designated as a "metallic water-cooled gas-producer."

The objects of my invention are, first, to construct a metallic water-cooled gas-producer in which sticking or clinkering of fuel to the wall of the metallic combustion-chamber may be obviated when run hot and fast, and it is consuming large quantities of fuel and producing a proportionately large quantity of gas; second, to obviate the objectionable features heretofore attending the use of producers provided with brick linings, in which the working has been very irregular and cleaning out or removal of the non-combustible matter difficult, rendering it practically impossible to run a producer for any length of time or to any reasonable capacity continuously, more particularly where anthracite coal or anthracite culm was used as the fuel for generating the heating-gas, and for the utilization of which fuel my present producer is especially well adapted; third, to drive the producer to much greater capacity, and hence necessarily make gas with greater uniformity, due to the fact that the producer can be worked continuously without stopping to clean out or remove the clinkers and ashes therefrom. The heat of the first combustion (C to CO) is usually lost, which in practice is unavoidable, and hence, such being the case, it matters not whether the heat be lost in brick walls or in metallic water-cooled walls, yet, nevertheless, the latter construction of a producer has this advantage that the heat imparted to the water may be utilized for

making steam for the blast or other purposes than those having special relation to the invention; fourth, to provide for the uniform admission and distribution of air or steam and air into contact with the fuel in the combustion-chamber from the lower portion of the producer for effecting combustion of the fuel and for obtaining the best practical results in the production of heating-gas for metallurgical and other operations; and, fifth, to provide a revolving bottom having mechanism for actuating the same, whereby all non-combustible matter may be readily, effectually, and continuously discharged from the producer while in full operation without the slightest interference therewith.

The nature of my invention will be more fully understood by reference to the accompanying drawings, wherein—

Figure 1 is a vertical central section through a metallic water-cooled gas-producer of my improved construction. Figs. 2 and 3 are respectively transverse sections of the metallic water-cooled gas-producer on the lines *xx* and *yy* of Fig. 1. Fig. 4 is a top or plan view of the flanged top plate of the producer, which forms a receptacle for containing a supply of water for keeping the upper portion of the producer cool, and the annular flanged rims cast therewith for the insertion of the feed-hopper, the gas-flue pipe, and showing also sight-apertures therein for examining the upper portion of the producer. Fig. 5 is a side elevation of the conical-shaped bottom, showing the interstices therein for the passage of the air therethrough and the projecting points arranged radially on the exterior surface of the revolving bottom for grinding up the clinkers accumulating in the combustion-chamber; and Fig. 6 is a vertical central section of my improved producer, on an enlarged scale, of the lower portion thereof, showing the conical-shaped revolving bottom with the interstices therein and the radial rows of points thereon, the "water seal," annular sealed ash-pit, and the central air or steam and air blast chamber, and the blast-pipe extending vertically into said chamber.

Referring to the drawings, A is the metallic main casing, made, preferably, cylindrical in

form, having a double flanged top plate, B, made of cast-iron or other suitable metal and so constructed and arranged that a receptacle is formed for containing a supply of water for preventing the heat of the producer from having a deteriorating effect upon the several parts attached to the top plate.

C is the gas-flue exit-pipe fitting around the annular rim e, cast with the flanged top plate, B.

D is the bosh-shaped feed-hopper fitting snugly against the inner flaring annular arm, e', of the top plate, B.

d is the bell for closing the hopper after the fuel has been supplied to the central combustion-chamber through the top thereof, and which fits snugly up against the throat of the hopper. This bell d is preferably attached to a vertical rod, d⁴, hinged to a cross-rod, d⁵, and to a depending lever-arm, d', pivoted to a bracket, d², secured to the casing of the feed-hopper D, which permits of the raising and lowering of the bell when desired; or the bell may be double lined with a sufficient space left between for the circulation of water admitted from any source. The manner of water-cooling the bell has not been shown, but the method of so doing will be manifestly obvious to those skilled in the art to which this invention appertains without illustration or further explanation.

I am aware that hoppers have long been used in brick-lined gas-generators; but I am not aware that a feed-hopper has ever been used constructed and arranged as described, and supported by a flanged top plate capable of containing a supply of water for keeping the upper portion of the producer at all times cool.

40 In the annular flanged top plate, B, is provided one or more sight-openings, N, having covers n, with eyes n' cast therewith, for handling, and which covers may be readily removed for ascertaining the condition of the fuel or for examining the upper part of the producer for whatever purpose it may become necessary.

E is a metallic combustion-chamber, preferably open at the top, and made of plate or 50 boiler iron in sections riveted together, and the chamber in form either bosh-shaped near the bottom thereof, as shown in Fig. 1, or constructed so that it will be of a uniform diameter from the bottom to the top, or only 55 slightly tapering inward in the direction of the top of the chamber, or of such other shape as will give the best results in practice in the use of anthracite coal or anthracite culm as the fuel for generating the heating-gas. The bottom 60 of the metallic combustion-chamber E is riveted to a flanged annular plate, e², which in a similar manner is attached to the metallic casing A. The rivets which hold the combustion-chamber E to the supporting-plate e² preferably 65 project laterally therefrom a short distance into the combustion-chamber E, and serve as grinders to act in conjunction with the points

g³ arranged radially around the exterior surface of the revolving bottom G for breaking up the cinder and clinkers accumulating in 70 the combustion-chamber E.

F is an annular space between the main casing A and the combustion-chamber E, and designated as a "jacket," for containing a supply of water admitted through a pipe, f, 75 extending downward from near the top of the main casing to within a short distance of the bottom of the plate e², secured to the main casing and supporting the combustion-chamber E in position, and the water or condensed steam and water discharged from the water-jacket near the top of the main casing through an overflow-pipe, f', suitably supported by a straightening-plate, f², fastened to the main casing A, but, however, below the open top 85 of the combustion-chamber E. The overflow-pipe f' is provided with a V-shaped trap, f⁴, as shown in broken section in Fig. 1, and in which trap a quantity of water will always be maintained for preventing any gas from escaping through the same instead of through the gas-exit pipe C.

I am aware that a generator for making hydrocarbon gas has been constructed with a rectangular closed interior shell or fire-box 95 boiler surrounded by a water-space on its four sides; but I am not aware that a metallic cylindriform combustion-chamber open at the top has ever been used or arranged in the manner described for burning anthracite coal or 100 anthracite culm for generating heating or similar gases, and in which clinkering or sticking of non-combustible matter to the wall thereof is obviated.

G is a conical-shaped revolving bottom made 105 of cast-iron or other suitable metal, with a series of radial narrow interstices or preferably narrow inverted-V-shaped openings, g', therein, and extending therethrough for the free passage of the air or steam and air admitted 110 by forced draft or otherwise through an underground conduction-pipe, J, provided with a hood, j, rigidly supported in position by the base-plate a, to which the wall of the main casing is riveted, and which pipe extends vertically into the cylindrical chamber H. The volume of air or steam and air discharged 115 therein through the pipe J is uniformly distributed through the openings g' of the revolving bottom G into contact with the fuel 120 in the central combustion-chamber, E, in a more or less state of incandescence for effecting both a uniform and complete combustion 125 thereof and preventing sticking or clinkering of non-combustible matter to the wall of the chamber E.

The conical-shaped revolving bottom is supported centrally in position by means of a post, g², in a cylindrical housing, g¹², having an annular flanged bottom, g¹³, which is riveted securely to the base-plate a of the sealed ash-pit I. Cast with the lower portion of the revolving bottom at suitable distances apart are projecting points or teeth for grinding up

the clinkers passing downward between the throat k of the combustion-chamber E and the revolving bottom G. This revolving bottom G is provided with an annular shallow trough, g , for containing a constant supply of water. Upon the under side of the trough g , near the outer periphery thereof, is a ratchet-surface, g^4 , and meshing therewith is a cog-wheel, g^5 , supported upon a horizontal shaft, g^6 , held in bearings g^7 , riveted to the metallic wall of the ash-pit I and the air or steam blast chamber H. This horizontal shaft g^6 carries a crank, g^8 , having a handle, g^{14} , for operating in a well-understood manner the conical-shaped bottom 15 around and around for breaking up the clinker and carrying the same, more or less broken up, together with the ashes, over the outer periphery thereof into the annular sealed ash-pit I. The water-trough g is provided with an annular rim, g^9 , for keeping the water from running over the peripheral surface of the bottom. The cinder and clinker dropping down through the throat k of the combustion-chamber into the trough is thus cooled off, together 20 with the ashes, preparatory to the precipitation into the annular sealed ash-pit I beneath, when the bottom G is revolved around and around by the attendant in charge.

The revolving bottom G, it should be borne 30 in mind, must necessarily be diametrically so proportioned to the throat k of the combustion-chamber E and at such distance therefrom that the superimposed incandescent mass will be supported thereby, and, furthermore, in order that the clinker and ashes passing downward between the throat of the combustion-chamber and the revolving bottom may be maintained in the water-trough g until discharged over the outer periphery thereof 35 40 into the closed ash-pit I by the operation of the crank g^8 , either around and around or backward and forward.

I am aware that a brick-lined gas-producer has been provided with a revolving grate of 45 spiral or step-like form having perforations therein and curved ribs or vanes thereon, and the grate supported by a bracket secured in the base of the ash-pit, and that air has been admitted directly into an ash-pit instead of 50 directly through the perforations in the grate. This arrangement is objectionable because, as a matter of fact, in practice the air, instead of passing through the narrow perforations in the grate, will pass upward around the outer 55 periphery thereof and follow the freest line of travel, which will be along the wall of the combustion-chamber, and hence combustion will be too rapid there and arches will be formed of the clinker; but I am not aware that 60 a metallic water-cooled gas-producer provided with a revolving bottom, such as shown and as hereinbefore described, has ever been used in which air or steam and air has been discharged radially and directly into the combustion-chamber into contact with the fuel in 65 a more or less state of incandescence without the formation of arches of clinker and stick-

ing of non-combustible matter to the wall of the combustion-chamber.

Cast with the revolving bottom G is an annular flange, g^{10} . To the wall of the air or steam and air blast receiving-chamber H is formed an annular channel, g^{11} , kept supplied with water from any suitable source and termed a "water seal," and into which the flange g^{10} is kept more or less immersed. This water seal, while keeping the underneath portions of the bottom cool, at the same time prevents the air or steam and air under pressure in the cylindrical chamber H from being diverted from its natural course through the interstices g' of the bottom G.

In the main casing A and the air or steam and air blast chamber H are provided one or more doors, suitably hinged to the respective metallic walls, as shown in dotted lines in Fig. 1, and which are preferably made large enough to admit a person into the ash-pit I and chamber H, for cleaning out the ashes in the former, and for whatever purpose it may become necessary for an examination to be made of the interior of the latter chamber, H.

The mode of operation of the metallic water-cooled gas-producer hereinbefore described may be explained in the following manner: 95 The fuel is fed into the central combustion-chamber, E, through the feed-hopper D by lowering the bell d a sufficient distance by the operation of the lever d' , and the required quantity of fuel being supplied to the combustion-chamber E, the bell d is then drawn upward snugly against the throat of the hopper D, and the air or steam and air by forced draft or otherwise admitted through the conduction-pipe J into the central chamber, H, 100 and in a vertical direction distributed radially, or nearly so, through the interstices in the conical-shaped bottom G into contact with the fuel in the combustion-chamber E for effecting combustion, and the gas arising from the 105 combustion of the fuel discharged through the exit-pipe C in the top of the producer for utilization, and whenever it shall become necessary during the time that the producer is making gas to remove the non-combustible 110 matter the crank g^8 may be revolved around and around by the attendant in charge, thereby discharging the ashes, together with the clinker, from the central combustion-chamber, E, continually dropping downward between 115 the throat k and the conical-shaped bottom into the trough g filled with water, over the outer periphery thereof, into the annular sealed ash-pit I without any necessity of stopping the producer while it is regularly making 120 125 gas.

It will be obvious to those skilled in the art to which my invention appertains that the conical-shaped revolving bottom and the upper and lower portions of the producer, with but slight modifications, can be adapted for use advantageously in a producer having brick-lined walls; and, again, by more thoroughly water-cooling the bottom by suitable

means for protection when the producer is run in the reverse way, that my invention is susceptible of being used for making water-gas for illuminating and other purposes.

5 In my application, Serial No. 236,746, filed May 2, 1887, I have claimed a bottom with a depending flange and with an ash-chamber having a chamber within the same, with a channel formed around said chamber, and 10 which channel, with said depending flange, forms a water seal, and therefore I do not wish to claim herein such constructions; but,

Having thus described the nature and objects of my invention, what I claim as new, 15 and desire to secure by Letters Patent, is—

The herein-described gas-producer with a bottom having narrow openings therein arranged in radial rows and mounted on a post which is supported in a housing, a cylindri-form casing beneath the bottom forming an 20 air or steam and air chamber, a pipe extending upward into said chamber, and means, as described, for rotating said bottom, substantially as and for the purposes set forth.

WM. J. TAYLOR.
